UNITED STATES PATENT OFFICE.

WILLIAM A. HEIDE, OF DETROIT, MICHIGAN.

CARBURETOR.

1,422,054.

Specification of Letters Patent.

Patented July 4, 1922.

Application filed June 26, 1917. Serial No. 177,087.

To all whom it may concern:

Be it known that I, WILLIAM A. HEIDE, a citizen of the United States, residing at Detroit, in the county of Wayne and State 5 of Michigan, have invented a new and useful Carburetor, of which the following is a specification.

The present invention relates to carburetors, and is particularly an improvement 10 over the carburetor disclosed in my co-pending application Serial No. 107,822, filed July 6, 1916.

The primary object of the invention is the provision of a novel and improved valve 15 structure for controlling the flow of fuel into the reservoir or float chamber whereby the liquid fuel therein is retained at a predetermined level.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed, can be made within the scope of what is claimed, without departing from the spirit of the invention.

The invention is illustrated in the accompanying drawings, wherein:—

Figure 1 is a vertical section through a carburetor constituting the present invention.

Figure 2 is a section on line 2—2, Figure 35 1.

In carrying out the invention, there is 40 provided a fuel receptacle or cup 1 having secured upon its rim a removable cover 2, which has seated thereon and extending diametrically across the same, the horizontal air suction pipe 3, provided at its discharge end with suitable means 4 for attaching it to the intake manifold or conduit of an internal combustion engine. The receptacle 45 1 is provided at a suitable point thereof above the fuel level with an air vent aperture 5.

A fuel cup 7 is engaged upwardly through 50 a central opening in the cover 2 and is threaded upwardly through the bottom of the pipe 3, said cup having an outstanding flange 7^a bearing upwardly against the cover 2. A fuel nozzle or tube 8 depends from the bottom of the cup 7 centrally thereof to 55 dip in the fuel within the receptacle 1, and the flow of fuel from the receptacle into the

lower end of the tube 8 is controlled by means of a valve 10 seatable against and cooperable with the lower end of the tube. The valve 10 is carried by and extends upwardly from the intermediate portion of a lever 12 within the receptacle 1 having one end (not shown) pivoted to a hanger (not shown) attached to the cover 2 and disposed adjacent to one side of the receptacle. 60 The other free end of the lever threadedly engages the lower threaded terminal 14 of a vertical stem or spindle 15 journaled for rotation through an upstanding lug 11 mounted upon the cover 2 at one side of the 70 pipe 3.

An air suction member 9 is fitted within the pipe 3, and the rim of the fuel cup 7 is threaded upwardly into said member 9, said member providing a constricted portion 75 of the air suction passage with which the mouth of the fuel cup 7 communicates.

The lug 11 is provided near one end with a fuel inlet passage 19, and a fuel supply pipe 19' is connected to the lug in communication with the passage 19, while a depending nipple 19^a connects at its upper end with the lug 11 and extends downwardly from the cover into the receptacle, to deliver the fuel into said receptacle. 85

In order to maintain the fuel level normal within the receptacle 1, a float 20 is provided therein, the same being hingedly connected at one side, as at 21, with the cover 2 and having openings 22 and 22', the 90 first mentioned opening accommodating the fuel tube 8, and the opening 22' accommodating a cap-shaped valve 23 seated upon an upstanding pin 24 carried by the hinged member 25 which is secured to the float. 95 The valve 23 can swing loosely upon the pin 24 and is seatable upwardly against the lower end of the nipple 19^a for shutting off the flow of fuel into the receptacle or reservoir 1. The upper conical end of the valve 100 23 can have a cover 23' of rubber or other compressible material, and it is preferable to provide an upstanding pin 23^a upon the apex of the cap 23 to enter the nipple 19^a and guide the valve. It is evident that when 105 the fuel level lowers, the float 21 swings downwardly, thereby permitting the cap 23 to unseat and allow the fuel to flow into the receptacle, and the float in being raised to normal position carries the valve 23 upwardly with the pin 23^a to seat said valve 110 and stop the flow of fuel. As seen in Figure

2, a U-shaped strip 25' is mounted on the pin 24 in the opening 22' surrounding the valve 23 with its upper terminals bent toward one another, as at 25^a, to overhang said valve, whereby should the valve fail to 5 seat by reason of becoming stuck to its seat, or for like reasons, the float in swinging downwardly will bring one or both of the fingers or terminals 25^a against the valve to force it from its seat.

The construction here shown and illustrated is considered the preferred embodiment of the invention but it is to be understood that the same may be modified and 15 altered in many respects, and that such limits of modification are governed only by what is claimed.

Having thus described the invention, what is claimed as new is:—

20 1. In a carburetor, a fuel reservoir, a float mounted therein, a fuel conduit extending in the reservoir and disposed above the float, a pin extending upwardly from the float, a

valve mounted loosely upon the pin and adapted to seat in the fuel conduit to close 25 the same, and means adapted to disengage the valve from the fuel conduit upon the descent of the float.

2. In a carburetor a fuel reservoir, a float mounted therein, a fuel conduit extending 30 within the reservoir and disposed above the float, a pin extending upwardly from the float, a valve loosely mounted upon the pin and adapted to seat in the fuel conduit to close the same, and a U-shaped member 35 mounted upon the pin and provided with inturned ends adapted to engage the valve to disengage the same from the fuel pipe upon the descent of the float.

In testimony that I claim the foregoing 40 as my own, I have hereto affixed my signature in the presence of two witnesses.

WILLIAM A. HEIDE.
